ATTORNEY

UNITED STATES PATENT OFFICE

SIMPSON LUTES, OF LOUISVILLE, KENTUCKY

POWER SHOVEL

Application filed October 7, 1931. Serial No. 567,483.

This invention relates to power shovels and is more particularly directed to a dipper tooth.

An object of the invention is the provision of a dipper tooth for use in connection with excavating and dredging machines and is so constructed that it will be tilted at an angle to the bottom of the scoop or shovel so that the teeth will always be directed towards the earth for not only causing even wear of both sides of the teeth but the proper thrusts will be maintained at all times.

A further object of the invention is the provision of a dipper tooth having a body portion which is secured in flat contact with the inner face of the bottom of a scoop, the body having an extension located at an acute angle to the bottom of the scoop and projecting outwardly and downwardly from the free edge of the scoop and a flat face on the extension having a bit secured thereto with the opposite edges of the bit being available for penetrating purposes when the bit is properly adjusted.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claim.

In the drawing:

Figure 1 is a side view in elevation of a scoop showing my invention applied thereto,

Figure 2 is a transverse vertical section taken on the line 2—2 of Figure 3,

Figure 3 is a longitudinal vertical section of the dipper tooth and scoop, and

Figure 4 is a fragmentary horizontal section taken along the line 4—4 of Figure 1.

Referring more particularly to the drawing, 10 generally designates a shovel or scoop adapted to be employed in connection with excavating machines and dredging machines in which dipper teeth are formed integrally

with the bottom face of the scoop or secured thereto, but such teeth are normally placed in a plane which is parallel to the plane of the bottom of the scoop so that the teeth extend directly forwardly in a direct line from the bottom of the scoop. In such constructions the dipper teeth do not have the proper angle so that when the scoop is thrust toward the ground the teeth will not always engage in the soil.

In the present instance the dipper tooth is provided with a body 11 having a cut-out portion 12 thereby leaving the side walls 13 and presenting a channel and a base portion 14. The outer face of the body is shown at 15^a and is substantially flat and lies in contact with the inner face of the bottom 15 of the scoop 10.

It will be noted that the outer face of the base portion 14 is stepped and passages 16 are provided to receive bolts 19. The heads 17 of the bolts are countersunk within similar openings in the bottom 15 of the scoop 10. The bolts extend through the base portion 14 and are secured in place by means of nuts 18 which rest upon the stepped sections of the outer face of the base portion 14. These bolts may be made square in order to prevent turning of the same and the passages 16 are similarly constructed.

An extension 20 projects outwardly and upwardly at an acute angle to the flat portion 15^a of the body of the dipper tooth. The inner face of the extension is stepped to receive nuts 21 threaded onto bolts 22 which are received by aligned passages in the extension and a bit 25. In order to provide the stepped sections the extension 20 is cut out to provide a channel 23 and side walls 24.

The bit 25 is secured in flat contact to the outer flat face 26 of the extension 20 by the bolts 22. The passages 27 are countersunk at one end and are spaced equal distances apart to receive the bolts 22 and also the heads 18^a. These bolts are square in cross section and the passages 27 are likewise similarly constructed in order to prevent turning of the bolts.

The forward edge of the bit 25 is provided with a bevelled cutting edge 28 which is

adapted to penetrate the ground when the scoop or shovel 10 is thrust toward the ground. The opposite end of the bit is square as shown at 29 and is adapted to be ground off at a proper angle when it is desired to use this end of the bit instead of the edge 28.

It will be noted that the bit 25 by the present construction is inclined at an angle to the bottom 15 of the scoop 10 so that the cutting edge 28 of the bit projects slightly below the inner face of the bottom of the scoop. Due to the angle of inclination of the bit 25 the dipper teeth will always be in a condition to penetrate the ground as the scoop is moved toward the ground at the proper angle.

The construction also provides for the ready removal of the bits 25 when it is desired to tool the bits and the spacing of the passages 27 provides for ready adjustment of the bits towards the outer free end of the extension 20. When the cutting edges 28 are worn down sufficiently so that they will require replacement, the bits may be turned around and the ends 29 sharpened to provide penetrating portions. Due to the equal spacing of the passages 27 the sharpened ends 29 may be placed in position where the cutting edges 28 are shown in Figure 3. In other words, the bits may be reversed at will and as the cutting edges wear down the bits may be shifted outwardly and secured in place by the bolts 22.

The angular disposition of the bits 25 also provides for equal distribution of wear on both sides of the cutting edges 28, thus preventing the unusual wear on the under face of the bits.

I claim:

In a power shovel, a scoop, a dipper tooth having a body which is triangular in shape thereby providing three faces, one face forming the bottom being flat and having a portion adapted to be secured to the inner face of the bottom of the scoop, the remaining portion of the flat face projecting beyond the outer edge of the scoop and having a groove formed therein, the bottom wall of the groove being stepped, the last-mentioned portion being provided with transverse passages to receive securing means for removably connecting a bit to another face which is inclined inwardly from the outer free end of the projecting end of the bottom face, the remaining face being inclined downwardly from the inner and second-mentioned face and provided with a groove, the bottom wall of said groove being stepped, the portion of the body between the first and last-mentioned faces having passages to receive securing means for connecting the body to the bottom of the scoop.

SIMPSON LUTES.
